UNITED STATES PATENT OFFICE.

EMIL HORN, OF MARCUS, WASHINGTON, ASSIGNOR OF ONE-HALF TO PETER E. CARROLL, OF MARCUS, WASHINGTON.

ROD-PACKING.

1,321,919.

Specification of Letters Patent.

Patented Nov. 18, 1919.

Application filed February 5, 1918. Serial No. 215,556.

To all whom it may concern:

Be it known that I, EMIL HORN, a citizen of the United States, residing at Marcus, in the county of Stevens and State of Washington, have invented a new and useful Rod-Packing, of which the following is a specification.

The subject of this invention is a rod packing wherein metallic rings are held in a suitable packing case, and the objects of the invention are, first, to provide a packing which will prevent leakage through the joint or stuffing box, second, to provide a rod packing which will automatically compensate for wear, third, to provide a simple, durable and efficient rod packing.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

Practical embodiments of the invention are shown in the accompanying drawing, 30 wherein:—

Figure 1 is a central longitudinal section of a preferred form of the device shown in place on a rod;

Fig. 2 is a similar view of a modified form 35 of the packing;

Fig. 3 is a view in elevation of a portion of one of the rings;

Fig. 4 is a similar view of a supplemental ring;

Fig. 5 is a view in elevation of another 40 form of ring.

Referring to the drawings by numerals of reference:

In carrying out the invention, a packing case 1 is provided which has a cap 2 threaded thereon at one end and which, at its opposite end, is concaved as indicated at 3.

Within the packing case 1 and having a 50 close sliding fit therewith, is a bull ring 4 which is countersunk at each end to form recesses for the reception of packing rings, each of which is formed of two rings or sections. One ring or section 5 is split as

shown and formed with an annular flange 7, 55 and has a lug 8 projecting inwardly from the flange 7 at a point diametrically opposite the split in the ring.

The supplemental ring 6 is also split and is formed to be seated upon the ring 5 within the flange 7. A cut out portion, indicated at 9, is provided at the split for the reception of the lug 8, which structure prevents the rings turning with respect to each other.

Seated on the cap 2 of the packing case 65 is a split tapering ring 10 which is adapted to enter the tapered opening 12 formed at one end of the throat ring 13. At the other end of the packing case a ring 14 is provided which is curved or convex at one face 70 to conform to the concave face 3 of the case.

It will be understood that the concaved end of the packing case; the cap; the throat ring; the ring 14; and the bull ring all have a close sliding fit on the rod 1'. The split 75 rings formed of the members 5 and 6 have an interior diameter which is less than the diameter of the rod, and the tapered ring 10 has an interior diameter slightly greater than the diameter of the rod. 80

These parts just described are, as usual, located within the usual stuffing box 15, which is closed by its gland 16.

The parts are assembled as will be understood from the foregoing and the gland 16 85 drawn against the stuffing box by any usual and well known means, (not shown). This draws the ring 10 tightly about the rod and forces the ring 14 firmly upon its seat. The split rings within the packing case act in the 90 usual manner to closely embrace the rod.

In the modified form shown in Fig. 2, a packing case 17 is provided which is offset outwardly at one end to form the annular projection 18 which is threaded interiorly to 95 receive the exteriorly threaded cap or plug 19.

A bull ring 20 is positioned within the casing with which it has a close sliding fit. This bull ring is countersunk at each end to 100 form annular recesses for the reception of the split rings 21 which are similar in all respects to the rings heretofore described.

The stuffing box 22 engages the annular projection 18, as shown, while the gland 23 105 engages the opposed side of said projection 18.

The gland is provided with an oil hole

24 communicating with the enlarged bore of the gland and a swab 25 may be provided in said bore to properly supply oil to the rod.

The ring 26 shown in Fig. 5 is an ordinary split ring divided by a diagonal slit 27. This ring may be used in place of the split rings just described, especially where low pressures are encountered. It may also be used in conjunction with the other rings 10 and may take the place of either one in the bull ring.

While the bull ring has been here shown and described as having only two split rings therein, it is understood that as many split 15 rings as desired may be arranged in the packing case.

Attention is also called to the fact that the split rings are so placed that the supplemental ring, 6, is always toward the gland. This is done so that no through slit or cut will be presented to allow the escape of fluid.

Having thus described the invention, what is claimed as new and sought by Letters 25 Patent, is:—

1. A rod packing, comprising a packing case, a bull ring in the case, split rings in the bull ring, a cap threaded to the case, a split tapering ring seated on the cap, a 30 throat ring, having a tapering opening for the reception of the tapering ring, contact-

ing the tapering ring, a stuffing box and a gland for the stuffing box.

2. A rod packing, comprising a packing case formed with a concaved end, metallic packing in the case, a cap threaded to the case, a split tapering ring seated on the cap, a throat ring, formed with a tapering opening at one end for the reception of the tapering ring, contacting the tapering ring, a stuffing box, and a gland for closing the stuffing box.

3. In a rod packing, a rod, a packing case mounted on the rod and having one end closed and its opposite end open and provided with interior screw threads, a bull ring on the rod and snugly received by the packing case, and provided with an annular groove at each of its opposite ends, a packing ring in each of the grooves, one of the packing rings bearing against the closed end of the packing case, and a gland positioned on the rod and threaded on the threaded end of the packing case and bearing against the adjacent packing ring.

In testimony that I claim the foregoing as my own, I have hereto affixed my signature in the presence of two witnesses.

EMIL HORN.
